UNITED STATES PATENT OFFICE

1,989,915

MONOGRAM UNIT

Michael Chernow, New York, N. Y.

Application April 19, 1934, Serial No. 721,290

11 Claims. (Cl. 40—140)

My present invention relates to improvements in monograms of the character which are manufactured, sold and handled as individual units and then bodily applied to a support therefor.

5 The term "monogram" is used for descriptive convenience only, and is intended to include letters, numerals, symbols, decorative devices, identifying characters and similar indicia. The "support" to which the monograms are applied may 10 constitute or form part of any of an infinite variety of devices, typical examples of which are cigarette cases, vanity cases, escutcheon plates, automobile doors, rings, plaques of glass, celluloid or metal, etc., the support being usually 15 smooth and hard.

An object of the invention is to provide monograms of the general character of those of my prior Patents No. 1,932,304 of October 24th, 1933, and No. 1,942,240 of January 2nd, 1934, which 20 admit of convenient handling and positioning without injury thereto, though in embodiments even smaller, thinner and flimsier than those for which the said prior patents have their preferred application.

25 Another object is to provide a monogram of the above type, the major area of which remains substantially unstrained, but which presents desirable structural modifications of the metal at the periphery thereof, that contribute to enhance 30 the security of the bond between the monogram and the support on which it is affixed.

Another object is to provide a monogram of the above type, which lends itself readily to mounting on curved supports or on flat surfaces 35 by ready adaptation under simple finger pressure in the course of application.

Another object is to provide a monogram, which though of fairly flimsy character, is not subject to twisting, warping or creasing in handling and which, in fact may be accurately positioned with ease, and securely affixed to a support, without the need for even touching the delicate monogram structure, and without the need for any tools for the purpose.

45 Another object is to provide an individual pack for a monogram of the above character, which affords adequate protection from mechanical injury, while freely exposing the monogram to view and which permits instant removal of the monogram from the pack for application to a support, without the possibility of injury thereto in the handling thereof.

In the accompanying drawing, in which are 50 shown one or more of various possible embodiments of the several features of the invention,

Fig. 1 is a plan view of a preferred form of monogram pack.

Fig. 2 is a longitudinal cross-section on a larger scale, taken on the line 2—2 of Fig. 1.

Fig. 3 is a dropped perspective view of the constituents making up the pack.

Fig. 4 is a perspective view illustrating the method of removing the monogram unit from the pack.

Fig. 5 is a perspective view illustrating the 10 mode of application of the monogram to a support.

Fig. 6 is a plan view showing the monogram installed.

Fig. 7 is a transverse sectional view on a larger 15 scale taken on the line 7—7 of Fig. 6, and

Fig. 8 is a diagrammatic view in longitudinal cross-section illustrating the manner of blanking out the monogram, in the manufacture thereof.

The pack and mode of use thereof, shown in 20 Figs. 1 to 5, while illustrated in association with a particular monogram structure more fully disclosed in Figs. 6 to 8 and hereinafter described, is applicable to flat or substantially flat monogram structures of other types, particularly to 25 such as are so small or so delicate as to be difficult to handle. Such monogram is illustratively shown at 10 in the pack of Figs. 1 to 5, and is illustratively shown as carrying a dried flexible cement 30 coating its entire rear surface and adapted to be softened by application of a suitable solvent (not shown).

The pack comprises a small envelope 12, preferably of translucent or transparent paper, of 35 generally conventional rectangular form including side flaps 13, a bottom flap 14, and a wide cover flap 15. The envelope has enclosed therein a stiffening card 16 on which may be printed directions for the application of the monogram, as suggested in Fig. 1. The monogram 10 is adhesively secured at its face preferably to substantially the middle of a rectangular blank 17, of translucent or transparent paper stock, comprising a carrier for the monogram and having a rectangular outline to fit with little clearance in the envelope 12. The carrier may also have a flap 18 beyond the limiting crease 19 of the body thereof, constituting a handle or finger tab.

40 The pack in closed condition appears in Fig. 1 and it will be seen that the printing on the back- 45 ing card 16 is visible through the two layers of the monogram carrier 17 and the face 12 of the envelope. No special legends need be printed on the envelope to disclose the identity of its 50 contents; since the face of the monogram 10, 55

adhesively secured to the back of the carrier 17 is exposed to view through the face of the envelope. The stiffening card 16 protects the envelope and its contents from being crumpled or creased before application or use of the monogram.

When the monogram is to be applied, the carrier 17 is removed from the envelope by its extension flap 18, as best shown in Fig. 4, with the monogram substantially a part thereof. Thereupon, solvent is applied by a brush to soften the dry cement on the rear face of the monogram. The monogram may now be readily positioned in the precise location desired, by handling merely the carrier 17 thereof, as best shown in Fig. 5, the monogram and the support being visible through the transparent carrier. Upon the application of finger pressure across the carrier, after the monogram has been positioned, the back of the monogram becomes securely bonded to its support. The carrier is now simply pulled off the affixed monogram.

The bond between the monogram and the carrier is preferably of less tensile strength than that of the paper carrier itself and of far less strength than the bond between the monogram and the surface to which it is affixed, so that the carrier in being pulled off will not tear or loosen the hold of the monogram to its support. Rubber cement 20 applied only in one or more dabs to localized parts of the monogram face preferably serves as the bond between the carrier and the face of the monogram. Such cement is desirable because it has a tendency, in the withdrawal of the carrier from the monogram, to adhere wholly to the non-metallic carrier, leaving practically no trace on the surface of the metal monogram. By greasing the face of the monogram before application of the dab or dabs of rubber cement, assurance is had that the cement comes off the monogram without leaving a trace, and adheres completely to the carrier. Accordingly, after the carrier is pulled off the mounted monogram, no further cleaning or polishing operation is necessary.

The invention is, of course, not limited to the precise character of cement or adhesive used for this purpose, although rubber or equivalent cement is preferred since, should the greasing step above set forth be omitted and a trace of adhesive stick to the metal face, such adhesive can be readily peeled off by simply rubbing the monogram face with the finger.

In the construction and mode of application set forth, it is readily seen that the monogram, however tiny or however flimsy, is positioned and applied with the utmost facility and without the need for even touching the same with a finger, and without the need for any tools.

While ordinarily a thin and strong paper tissue is preferred for the envelope 12, and the carrier 17, it is understood that regenerated cellulose of the type commonly known as "Cellophane" may be used for the envelope and, if desired, also for the flexible carrier.

The preferred form of initial is of thin metal stock, usually in the order of .005" or less in thickness, preferably of a soft bendable metal 10 having a highly polished or, if desired, a dull face 10' of gold, silver, chromium or other hardened plated or colored surface. The hard surface may be electroplated on the soft backing, or, if desired, may be a distinct lamination suitably bonded to the face of the softer backing. As a consequence the blank, while flexible and non-

elastic, nevertheless has a hard surface and in mounted position on a rigid support, is not subject to being creased, bent or broken and has excellent wearing properties. The sheet metal stock from which the monograms are stamped, made of soft metal and faced as set forth, has its back preferably coated with dried water-insoluble cement.

The monogram is stamped out by a die of special construction designed to preclude the distortion of the body of the monogram, inevitable with ordinary dies. According to a preferred embodiment, diagrammatically shown in Fig. 8, of stamping apparatus to bring about this result, the anvil member 25 comprises a slideable plunger having a support ledge 26 travelling in a guide 27 in the support 30, and held by a powerful coil spring 28 against stop flange 29 to protrude in uppermost position above the face 31 of the support.

The blank B from which the monogram is to be stamped, is laid upon the elevated top of the spring-pressed plunger 25 which has the outline of the monogram, to be depressed by the action of the corresponding die or hammer member 32. Upon depression of the latter, the blank B is first securely clamped throughout its area, against the plunger 25 and thereby held in the blanking operation against any possible distortion of its main area. The main area of the monogram is thus depressed below the face 31 of the support and its periphery is sheared and forced between the support 30 and the lower end of hammer 32. The stamped out monogram is released by return of the coil spring 28 after the hammer 32 has lifted, preparatory for the next blanking operation.

As shown in the drawing, the hammer 32 is preferably slightly convex at its operating face and the anvil 25 correspondingly concave, which produces a correspondingly slightly dished blank, although, if desired, by use of flat ended elements 32-25, a blank perfectly flat, as to its main area, may be produced.

In the stamping operation, while the area of the monogram is securely clamped against any possible distortion by the tremendous resistance of the coil spring 28, the metal of the monogram becomes slightly dished as desired, and is otherwise distorted only at the peripheral area thereof to form a shallow ridge, best shown at 35 in Fig. 7, and extending substantially completely about the periphery of the blanked monogram. This ridge 35 is of height in the order of .002 inch, and serves to stiffen the monogram somewhat, for which reason it is feasible to use even thinner stock than with monograms prepared according to the teachings of either of the prior patents above identified. The ridge 35 affords a tray or trough of depth extending at least to the level of the thickness of dried cement film 11, covering the rear of the sheet stock from which the monogram is stamped. If desired, however, the cement may be applied to the back of the monogram after the latter has been blanked out.

The slightly dished monogram conforms readily to any curved surface to which it may be desired to affix it, assuming greater or lesser curvature as the case may be, under the pressure of the finger, to conform to the curvature of the mounting surface and this without the possibility of buckling. By virtue of the non-resilient stock of the monogram, it does not tend to bend away from its mount after it has been affixed.

In the applied monogram, as best shown in 75

Fig. 7, the previously softened dry cement 11 is confined within the closed space determined by the ridge support 35, and the rear face of the monogram, thereby confining the cement against 5 escape beyond the edge of the monogram, thus, on the one hand, assuring a secure bond which utilizes all the available cement, and on the other hand, dispensing with the need for removal of cement that otherwise might spread beyond the 10 rim of the monogram. Fig. 7 illustratively shows the monogram applied to a flat surface to which it readily adapts itself under finger pressure even though initially dished, as set forth.

The construction of monogram set forth has a 15 further particular utility in cooperation with the carrier 17, for none of the cement 11 from the back of the monogram can reach the carrier 17 and so the consequent difficulties are precluded, of accidentally pasting the carrier to the support by 20 exuding cement, in the course of applying a monogram to a support.

It will thus be seen that there is herein described an article in which the several features of this invention are embodied, and which article in its action attains the various objects of the 25 invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in 35 a limiting sense.

Having thus described my invention, what I claim as new and desire to secure by Letters Patent of the United States is:—

1. As a new article of manufacture, a bendable 40 metal monogram constituting a stamping strained substantially solely at its periphery, the metal thereat presenting a ridge protruding peripherally about the blank from one face thereof, said blank with its ridge forming a flat tray, dried substantially water-insoluble cement of a flexible character substantially filling said tray, and adapted to be softened by a solvent, whereby the ridge of the monogram applied to a supporting surface 45 will confine the cement in a closed chamber between the support and the monogram.

2. As a new article of manufacture, a unit comprising a monogram of thin, flexible sheet material having flexible dried cement covering the rear face thereof and of character adapted to be 50 softened by a solvent, said monogram having releasably bonded to the face thereof a translucent, flexible carrier for facilitating positioning and mounting of the monogram.

3. As a new article of manufacture, a flexible 55 sheet metal monogram having dried cement coating the rear face thereof, a transparent flexible carrier considerably larger than and bonded to the face of said monogram, the latter bond being a relatively feeble one to separate readily when the carrier is withdrawn by a simple pull from the face of the monogram after the latter has been 60 mounted.

4. The combination set forth in claim 3 in which 65 the cement connecting the monogram to the carrier is of adhesive strength less than that at the back of the monogram, or than the tensile strength of the carrier.

5. As a new article of manufacture, a thin sheet metal monogram having substantially the entire area of the rear face thereof coated with a dry, flexible, water-insoluble cement and a translucent flexible carrier connected by rubber cement to the face of said monogram, for facility in handling, positioning, mounting and then freeing the monogram from the carrier. 5

6. As a new article of manufacture, a thin, sheet metal monogram having the area of the rear face thereof coated with a dry, flexible, water-insoluble cement, the face thereof having an oleaginous coating, and a translucent flexible carrier connected by rubber cement to said face, whereby the monogram may be readily positioned without direct handling thereof, and after adhesion of the monogram to the support, the carrier may be pulled off the monogram, leaving the latter free from cement. 10 15

7. As an article of manufacture, a thin, flexible metal monogram having a narrow ridge protruding outward from the periphery of the rear face thereof, dried cement coating substantially the entire area of said monogram enclosed by said ridge, a translucent flexible carrier for said monogram, a rubber cement adhesive bond connecting said carrier to the face of said monogram at a limited area of the latter, whereby after treating the back of said initial with an appropriate solvent the translucent carrier may be manipulated, correctly to position the monogram with respect to a supporting surface therefor, and after exerting pressure through said carrier, the latter may be removed by a single pull from the face of said monogram, the rubber cement 20 25 substantially adhering to the carrier, and the ridge confining the cement at the back of the monogram, and preventing contact of such cement with the carrier. 30 35

8. As a new article of manufacture, a monogram comprising a thin, soft flexible non-resilient metal blank having a peripheral ridge, a thin hard metal facing constituting a unitary part of said blank and dried flexible cement covering the rear area of said monogram and enclosed by said 40 45 ridge, whereby the monogram when affixed will be protected from injury and its facing will constitute a durable wear surface.

9. As a new article of manufacture, a metal monogram of slightly dished construction, concave at its rear and convex at its face, and a layer of dry, flexible cement coating the rear, the monogram being pliable and non-resilient for ready adaptation under pressure to the form and curvature of a supporting surface, said monogram comprising a body of soft, non-resilient metal, said monogram having a thin, hard, protective exposed facing of hard metal. 50 55

10. As a new article of manufacture, a soft, flexible, non-resilient metal monogram comprising a body of soft, non-resilient metal of slightly 60 dished shape, having a peripheral ridge about the concavity thereof and flexible dry cement filling the area enclosed by said ridge, said monogram having a thin facing of hard metal affording an exposed wear surface when the monogram is affixed to a support.

11. As a new article of manufacture, monogram sheet stock comprising a layer of thin, soft non-resilient metal, a thin hard metal facing 70 unitary therewith and dried flexible cement backing unitary therewith.

MICHAEL CHERNOW.
